UNITED STATES PATENT OFFICE.

SEVERN WINBERG, OF GALESBURG, ILLINOIS.

SPIRIT-LEVEL AND PLUMB.

SPECIFICATION forming part of Letters Patent No. 710,388, dated September 30, 1902.

Application filed March 27, 1902. Serial No. 100,249. (No model.)

To all whom it may concern:

Be it known that I, SEVERN WINBERG, a citizen of Galesburg, in the county of Knox and State of Illinois, have invented certain new and useful Improvements in Spirit-Levels and Plumbs, of which the following is a specification.

This invention relates to spirit-levels and plumbs of that general type or class known as "builders' levels;" and it consists in constructions and combinations of parts which will be hereinafter described, and pointed out in the claims.

The principal objects of the invention are to provide a level and plumb, or either of them, which will be economic of manufacture, durable in use, difficult to break or get out of order, in which the tube may be removed if broken and another substituted therefor, which is adjustable, which is convenient in use, and in which the level-tube "sight" or bulb therein is visible and uppermost in whatever position the level-stock is held.

Further objects of the invention will hereinafter appear.

In the accompanying drawings, in which similar letters of reference indicate similar parts in all the figures thereof, Figure 1 is a top plan of my device partly broken away to show interior parts and also to economize space. Fig. 2 is a plan section in the line 2 2 in Fig. 3. Fig. 3 is an end elevation. Fig. 4 is a side elevation of parts. Fig. 5 is a sectional view in the direction of the arrows on line 5 5 in Fig. 2. Fig. 6 is an end elevation of one section of the level-tube-containing cylinder. Fig. 7 is a side elevation of the level-tube-containing cylinder, partly broken away; and Fig. 8 is a side elevation of the same cylinder, showing its parts disjointed.

I will hereinafter describe only that part of my invention which relates to a level, it being understood that that part of the invention which relates to a plumb is constructed and operates in the same manner as does the level. In Fig. 1 I have not shown the adjusting parts in that part thereof which relates to the plumb.

Referring to the drawings by letters, A represents the level-stock, which is preferably of

wood and rectangular in form; B, a frame in and upon which the operating parts are mounted; C, an adjusting-plate; D, a boss on said plate, which boss is screw-threaded to receive an elongated screw E, which extends to within a short distance of the edge of the level-stock, where its head F rests against a shoulder G in said stock. A screw-plug G', which rests beneath and is held in place by a metallic plate G², retains the head F of the screw E in place and prevents injury thereto or dislodgment thereof, but permits of its ready withdrawal or adjustment when said plug G' is removed. The plate G² is held in place in the stock in any desired or preferred manner. Through the extended end B² of the frame B are slots B³, Figs. 3, 5, and 6, through which the adjustable plate C passes to slide freely back and forth therein. In said plate and at about its central longitudinal part is an opening c for the reception of a stud or journal c', which projects from the outer end of the part K² of the level-tube-containing cylinder at or near its peripheral portion. In the extended outer end B⁴ of the frame B is an opening b for the reception of a screw b', which is threaded into the outer end of the part K' of the cylinder K (hereinafter described) at or near its peripheral portion. The parts c' and b' are loosely journaled in their respective bearings to swing freely therein.

H H are cap or retaining plates on either side of the level-stock, which plates retain the frame B and its contained parts in position in said stock. In these plates observation-disks H' are mounted. The cap-plates and observation-disks prevent breakage of the level-tube and act as a protection from dust, dirt, and the elements.

Within the frame B and longitudinally thereof is the level-tube J and its containing cylinder K, a part of which cylinder is cut away in the usual manner. The cylinder consists of two parts, a longer part K' and a shorter part K², which latter part is telescoped within or into the part K'. A journal or pin c' projects from the outer end of the part K² near the periphery thereof, as shown best at Figs. 7 and 8. A short screw b' (which is first passed through the part B⁴ of the frame B) is threaded into and projects from

- the outer end of the part K' of the cylinder near the periphery thereof. The tube J is firmly fixed in the part K', and the part or extension K² is then telescoped into said part 5 K', into which it fits snugly, thereby maintaining the parts in the desired relation to each other—that is, the parts c' and b' in a longitudinal line with each other and with the bulb or sight J' in the level-tube J.
- 10 Should the level-tube become broken or should it for any reason become desirable or necessary to insert another tube, it may be readily and easily accomplished as follows: The screw F being withdrawn from the boss 15 D and one of the cap-plates H removed, the frame B and its contained parts is lifted out of the stock A. The part K² is then withdrawn from the longer part K' of the cylinder K, the old or broken tube removed from 20 said part K' and a new one fixed therein in proper position, and the part or section K² again telescoped into the part or section K'.
- The parts are assembled as follows: The 25 level-tube J being properly and rigidly fixed in place in the cylinder K, the pin c' and the screw b' being in a longitudinal line with each other and with the bulb in the tube, said pin c' is inserted in the opening c in the plate C, which plate is in its place in the slots B³ in 30 the extended end B² of the frame B. The screw b' is then inserted or passed loosely through the opening in the extended end B⁴ of the frame B and is threaded into the screw-threaded opening in the end of the part K' of 35 the cylinder K, thereby securing the level-tube and the cylinder K in proper position within the frame. Said parts are then placed in position in a hole or opening extending through the level-stock and the cap-plates 40 fastened in place, as shown best at Fig. 1. The screw E is then threaded into or through the boss D through a mortise L in the level-stock.
- 45 Adjustment of the level-tube and cylinder is effected as follows: The head F of the screw E resting, as it does, against the shoulder G in the mortise L in the level-stock and being threaded into the boss D on the adjustable plate C, when said screw is turned to 50 farther enter said boss it will raise said plate, and thereby the adjacent end of the cylinder and level-tube. When the screw is turned in the opposite direction, the result or effect will be the reverse. The screw-plug G' is 55 used only to gain or prevent access to the head F of the screw E and to prevent displacement thereof. The pin c' and screw b' being loosely journaled in the openings or journal-boxes c and b allow the cylinder and 60 level-tube to swing freely therein. Said cylinder and tube being suspended from journals located near the peripheral edges of its ends and said journals being in a longitudi-

nal line with each other and with the bulb in the level-tube, the diametrically opposite 65 side of the cylinder will descend by gravity, and in whatever position the level is placed the bulb will always remain uppermost.

When the device is used as both a level and plumb, the parts are located the level 70 about the central longitudinal part of the stock and the plumb about one-third the distance from the end of the stock to its median part. When it is desired to use it for battering, (the plumb only being then used,) 75 any desired inclination may be secured by adjustment of the screw E. (Not shown in that part of Fig. 1 relating to the plumb, but corresponding to said screw elsewhere shown in the drawings.)

I do not wish to be understood as limiting my claims to the exact manner of mounting the cylinder in the frame B at the end B⁴ thereof, as it may be done in any desired or preferred manner. I have accomplished it 85 as follows: A pin b², similar to the pin c', is fixed to the cylinder, as shown at Fig. 8. This pin is loosely journaled in a bearing in the inner end of a set-screw which is threaded into and through the end B⁴ of the frame B, 90 thereby effecting a similar result. When it is desired to remove the cylinder from the frame B, it may be readily and easily done by simply loosening the screw, thereby releasing the pin and cylinder.

Having thus described my invention, what I claim as new, and desire to secure by Letters Patent, is—

1. In a spirit-level, and in combination, a stock, a cylinder containing a level-tube, an 100 adjustable plate in which one end of said cylinder is journaled, the other end of which cylinder is journaled in a bearing in a frame, and an adjusting-screw for raising and lowering said plate and thereby one end of the 105 level-tube, substantially as described and shown.

2. In a spirit-level, and in combination, a cylinder containing a level-tube, an adjustable plate in which one end of said cylinder 110 is journaled, the other end of which cylinder is journaled in a bearing in a frame inclosing said parts, and said frame inclosed in a level-stock, and means for raising and lowering said plate and thereby the adjacent 115 end of the cylinder, substantially as shown and described.

3. In combination in a spirit-level, the level-stock A, the frame B, the cylinder K, the sliding adjustable plate C and the screw E, 120 all substantially as shown and for the purpose described.

SEVERN WINBERG.
